UNITED STATES PATENT OFFICE.

DANIEL EDWARD MORAN, OF NEW YORK, N. Y.

SAND-DRIER.

SPECIFICATION forming part of Letters Patent No. 550,798, dated December 3, 1895.

Application filed June 6, 1895. Serial No. 551,814. (No model.)

To all whom it may concern:

Be it known that I, DANIEL EDWARD MORAN, of the city of New York and State of New York, have invented a new and useful Improvement in Sand-Driers, of which the following is such a full, clear, and exact description as will enable others skilled in the art to make and use the same, when taken in connection with the accompanying drawings, 10 in which—

Figure 1 is a vertical section through the sand-drier. Fig. 2 is a horizontal section on the line X X of Fig. 1. Fig. 3 is a detail of construction. Fig. 4 is a vertical section of 15 a modification. Fig. 5 is a vertical section of a portable drier, and Fig. 6 is a cross-section of Fig. 5 on the line Y Y. Fig. 7 is a section of another modification.

This, my invention, relates to driers for 20 sand or other material; and it consists of a series of pockets or other receptacles made of perforated metal or wire-netting in which the wet sand is held until dried, or partially dried, by a current of air. When the sand is 25 partially dried, it falls through the netting, passing through the air and falling on a sheet of metal set at an angle so that the dried sand will pass down it to an opening, from which it is removed. In order to insure 30 that the air will act as a drying medium it is generally expedient to heat it, thereby increasing its capacity for moisture, and I have therefore provided a furnace.

The furnace is made, preferably, of a square 35 or oblong form, of brick, as shown in Fig. 2, having the four walls A, B, C, and D. At the bottom or lower part of the furnace is the grate E, having the usual ash-pit F and upper door G and lower door H. Across the 40 furnace is placed the metal sheet or deflector, plate I, being built in the walls A, B, and D, but with an opening between its lower edge and the wall C. Above the deflector-plate I are the pockets K K K K, made of wire-netting, 45 perforated sheet-iron, or like material. These pockets K K K K are attached to channel-iron beams L L L L, which extend across the walls B D, being embedded therein, the beams L L L L being placed sufficiently far apart to 50 accommodate the pockets K K K K between them. In the center of the channel-iron beams L L L L are holes M at various inter-

vals, over which are placed pipes O O O O, provided on their top with caps P P P P, of any suitable form, and above this is a conical roof ending in a smoke-stack Q. In the wall A, above the beams L L L L and pockets K K K K, is the door R, through which the sand to be dried is introduced. Below the lower edge of the deflector-plate I in the wall C is an opening or outlet S, near which the dried sand as it comes from the deflector-plate I is dropped, so that until removed it will close the opening S. Passing through this opening is shown the pipe T, of any suitable 65 size or shape, open at each end for the inlet of air. The heated sand lying on the pipe raises it to a high temperature and causes the air flowing through it to absorb heat from the sand which has been dried in the drier, thereby 70 increasing the capacity of the air to absorb moisture and making it available to dry other sand. This may be omitted without departing from the nature of my invention.

A small plate U may be placed over the inlet-pipe T to prevent sand from falling in it, or, if desired, this may be omitted.

In Fig. 3 is shown in detail the arrangement of the pockets and cross-beams, where the pockets, which are long and extend from one 80 side to the other of the furnace, are at their edge fastened to the beam by a strip of metal screwed or riveted thereto; but the manner of the fastening of the pocket to the beam forms no part of the invention, as various devices 85 may be used for that purpose.

In Fig. 4 is shown a modification of my drier, in which the pockets K' K' K' K' are made of wire-netting or perforated sheet metal supported by beams V, extending 90 across from and supported in the walls B D. This arrangement of pockets is found desirable under some circumstances, and when the sand is not put in in heavy layers there will be sufficient outlet for the air or products 95 of combustion without the necessity of the holes M. (Shown in Fig. 2.) Beneath these pockets is arranged the deflector-plate I, as in the other form of construction.

I may use the grate, as shown in Fig. 1, or 100 may introduce beneath the plate I a pipe W, having outlet-pipes Y thereon. Through this pipe W and outlet-pipe Y is introduced a current of hot or dry air, which may be ob-

- tained from any source. The pipe T, which lies in the hot sand and through which hot air is introduced in the chamber, may be furnished with an extension t, across which the discharge from the pipe Y passes, creating an in-current. The hot air passes against the deflector-plate I around the lower edge and through the openings in the wire-netting or perforated metal of the pockets K'. This arrangement for the use of hot air is particularly adapted when the drier is used in connection with or near iron or other furnaces where there is hot air or hot gases which are ordinarily allowed to escape. The pocket shown in Fig. 1 or Fig. 4 may be used with the hot-air blast generated either by the furnace of Fig. 1, or in any other manner, without departing from the nature of this my invention.
- 20 Instead of introducing hot air through the pipe W, I may introduce by means of a blower or air-compressor a current of air without heating it, as shown in Fig. 7 of the drawings, wherein the air is supplied to the distributing-pipe W by the blower and through the distributing-pipe W to the distributing-pipe g, as in many states of the atmosphere such current would be efficient in drying the sand and operating the drier.
- 25 Fig. 5, being a vertical section of a portable drier, shows the walls 1 made of sheet metal having the pockets K K K, and in addition to the pockets of the other form of drier an annular pocket 2, formed on one side by the wall 1 of the drier and on the other side by a perforated metal or netting 3, being open at the top, so as to admit sand when introduced through the door R above the pockets. This annular space, in fact, forms one pocket for 30 sand and at the same time acts as a preventive of radiation from the walls 1 of the furnace. The other parts of the drier, as over the grate E, are provided with fire-clay lining 4, as may be the walls over the pockets 5 6. This drier is shown made in a circular cross-section. It may, however, be made square or oblong. It is also provided with a deflector-plate I and discharge-outlet S, as the other forms of construction heretofore described, a 45 vent pipe or flue Q, and a door R, through which the sand is delivered to the pockets.
- 50 Having described the construction of the driers, I will now proceed to set forth the mode of operation.
- 55 The air introduced through the pipe W, in the form shown in Fig. 4, and the products of combustion from the fire on the grate E, in the construction shown in the said drawings, comes in contact with the plate I, is deflected by it, passing around the lower edge of it, up over its surface against the pockets K K K K, and between the pockets through the holes M in the channel-irons, or through the perforations of the perforated iron or wire-netting, to the upper chamber, and thence out through the vent-pipe Q. Wet sand, or sand that is to be dried, is thrown in the

pockets K K K K through the door R until the pockets are filled; and the sand may be thrown in to a height equal to the said pipes 70 O, where such pipes are used, or so as to thinly cover the upper part of the pockets by the beams V V V, in Fig. 4. The air or products of combustion passing between the pockets and through the perforations to a certain extent carries off the moisture of the sand and removes the coherence due to the moisture, causing the dried sand to fall through the perforations in the sheet metal or wire-netting, falling through the air into the chamber below the pockets on the plate or slide, across which it passes, coming in contact with the air to the lower edge into the pile of sand at the outlet-opening S. When heated air or a furnace is used, this pile of sand is hot 80 and heats the pipe T, which is placed so as to be in the pile of sand, through which pipe air passes to the inside of the drier below the slide-plate I, absorbing in its passage heat from the heated sand. The opening in 90 the perforated metal or wire-netting of which the pockets are formed is from one-eighth to three-quarters of an inch, or of such size as dry sand will readily pass through. I have found that about one-quarter inch gives good 95 results, although the degrees of fineness and the degree of moisture of the sand introduced and the freedom from moisture required may require a variance from the size of the perforations specified.

100 The slide-plate I is set at such an angle that moist sand will stick to it, while dry sand will slide on it, and I have found that the angle shown in the drawings, Fig. 1, gives good results. I may, however, use a plate or slide I more nearly vertical than shown, so as to carry the sand immediately to the outlet S.

110 What I claim as new, and desire to secure by Letters Patent, is—

1. The combination in a sand drier of perforated sand pockets having perforations of such size as to retain the damp sand and allow the dry sand to pass through, with an air-blowing apparatus arranged to introduce air 115 in a chamber beneath the sand pockets and discharge the same above the sand pockets, substantially as specified and set forth.

2. The combination in a sand drier of perforated sand pockets; air chamber beneath the same; deflector plate beneath the pockets; and air-blowing apparatus arranged to introduce air in a chamber beneath the sand pockets and discharge the same above the sand pockets, substantially as specified and set forth.

3. The combination in a sand drier of perforated sand pockets; deflector plate inclined toward the outlet of the drier, so as to discharge the sand at the outlet of the drier and seal the same by the dry sand, substantially as specified and set forth.

4. The combination in a sand drier of perforated sand pockets; vent pipes between the

same; and an air-blowing apparatus arranged to introduce air in a chamber beneath the sand pockets and discharge the same above the sand pockets, substantially as specified and set forth.

5. The combination in a sand drier of perforated sand pockets; hot-air blowing appa-

ratus; and air inlet pipes passing through the dried sand, substantially as specified and set forth.

DANIEL EDWARD MORAN.
